UNITED STATES PATENT OFFICE.

GEORGE U. BRAKE, OF FORT WAYNE, INDIANA, ASSIGNOR TO TOKHEIM OIL TANK AND PUMP COMPANY, A CORPORATION OF INDIANA.

SELF-MEASURING BARREL PUMP.

Application filed July 17, 1922. Serial No. 575,555.

This invention relates to improvements in self measuring barrel pumps adapted for dispensing oil, especially thick lubricating oil. The object of the invention is to provide in a pump of its class a valve for its piston head which will be positively opened and closed as the piston head is actuated in correspondingly opposite directions.

Ordinarily, where a valvular piston is employed in a pump, the valve is seated and unseated during the operation of the piston by the pressure of the transient liquid contained in the pump cylinder beneath or above the piston according to the direction of movement of the piston, the action of the valve being dependent upon movement of the piston head. The present invention contemplates the positive opening and closing of the valve in the piston head by the actuating mechanism for operating the piston head, and thus insure a more accurate measurement of the liquid dispensed by the pump.

The object of the invention is accomplished by the construction illustrated in the accompanying drawings, in which:—

Fig. 1 is a front elevation of a pump embodying the invention, a portion of the view being broken away;

Fig. 2 is a top plan view of the piston valve;

Fig. 3 is a side view of Fig. 2;

Fig. 4 is a top plan view of the sustaining disc of the piston head;

Fig. 5 is a central section of Fig. 4; and

Fig. 6 is a fragmentary sectional view of the pump cylinder showing the valvular piston head.

The characters appearing in the description refer to parts shown in the drawings and designed thereon by corresponding characters.

The invention comprises a pump cylinder 1 arranged between a base 2 and head 3, the latter having a discharge spout 4, and the base having a chamber 2' and an inlet valve 5. The head 3 has a tubular extension 6 at its top, the extension being closed at its upper end by a cap 7. A screw stop 8 extends centrally through the top of the cap into the tubular extension for the purpose hereinafter described.

Within the cylinder is a rack-bar 9 that extends through the head 3 into the extension 6 and has actuated relation with a cranking

means which includes a pinion 10 and crank 11, the pinion being contained within the head and connected with the crank. The lower end of the rack-bar has a stud 12 that extends loosely in a sustaining disc 13 which together with a leather cup 14 and retaining ring 15 form the piston head. An annular expanding member 16 is held by the retaining ring in position against the inner wall of the cup in the usual manner to hold the cup into intimate contact with the adjacent inner wall of the pump cylinder. The sustaining disc has a concentric series of openings 17 encompassed on its bottom by an annular valve seat 18, and a valve 19 fixed on the lower end of the stud 12 bears upon the seat when the rack-bar is raised. The disc 13 has also a central hub 20 through which the stud 12 loosely extends and against the upper end of which the rack-bar bears when the valve 19 is moved to open position. The lower end of the rack-bar and the valve on the stud are spaced apart sufficiently to admit of limited longitudinal movement of the stud in the piston head so that opening and closing of the valve is directly effected by movement of the rack-bar and the movement of the piston head is secondary to that of the valve.

In the operation of the invention the base 85 is screwed into the bung opening of a barrel or otherwise mounted in operating position. Also, a suction pipe (not shown), commonly employed, is connected with the lower end 90 of the base, through which liquid may be drawn into the pump. By manipulating the crank in the usual manner the rack-bar 95 is reciprocated. As the rack-bar is raised, the valve 19 bears against the seat 18, thus the openings 17 in the piston head are closed and the piston head is raised by the upward movement of the rack-bar through the medium of the valve 19. As the piston head is thus raised the liquid is drawn past the valve 5 in the base into the cylinder, the 100 amount depending upon the extent of upward movement of the rack-bar which is limited by coming into contact with the screw stop 8. When the rack-bar is moved downward, the stud slides in the piston head 105 until the valve 19 is open and the rack-bar bears against the hub and thus directly moves the piston head downwardly while the valve 19 is held out of contact with its seat, thus admitting the passage of the 110

liquid previously drawn into the lower end of the cylinder to pass through the openings in the piston head into the upper end of the cylinder, from which it becomes discharged through the spout 4 upon the subsequent upward stroke of the piston head.

The downward stroke of the piston head is limited by its sustaining disc which comes into contact with the base 2 upon reaching the lower end of the cylinder and the valve enters the chamber in the base displacing more or less of the liquid contents thereof. By adjusting the stop-screw 8 the stroke of the pump and the quantity of liquid discharged by the pump upon each stroke thereof may be regulated accordingly.

The chamber 2' in the base is of a size that admits of ready movement of the liquid therein around and about the valve 19,

which, especially when the liquid is an exceedingly heavy oil, facilitates operation of the pump.

What I claim is:—

A measuring pump including a cylindrical body having a discharge outlet at its top, a base having a chamber therein with a valve controlled inlet; a reciprocating piston having a valve opening and limited downward movement in the cylinder; and a driving member for the piston including a valve operable to close the valve opening therein and actuate the piston in its upward stroke, said valve being movable into said chamber at the end portion of the downward stroke of said driving member.

In testimony whereof I affix my signature.

GEORGE U. BRAKE.
